United States Patent Office

Des. 229,731
Patented Jan. 1, 1974

229,731

CHAIR

Francis B. Walsh, 1865 Charmelton St.,
Eugene, Oreg. 97401

Filed Mar. 6, 1972, Ser. No. 232,357

Term of patent 14 years

Int. Cl. D6—01

U.S. Cl. D6—70

FIG. 1 is a perspective view of a chair embodying my new design,

FIG. 2 is a front elevational view of the chair,

FIG. 3 is a top plan view,

FIG. 4 is a side elevational view, and

FIG. 5 is a rear elevational view of the chair.

I claim:

The ornamental design for a chair, as shown.
